UNITED STATES PATENT OFFICE.

HERMON S. ADAMS AND BYRON FAY, OF CLEVELAND, OHIO.

DESIGN FOR A MUCILAGE-BOTTLE.

Specification forming part of Design No. 6,158, dated October 1, 1872.

To all whom it may concern:

Be it known that we, HERMON S. ADAMS and BYRON FAY, of Cleveland, county of Cuyahoga and State of Ohio, have invented a Design for Mucilage-Bottles, of which the following is a specification:

The nature of our design is fully represented in the accompanying drawing, to which reference is made.

A represents the body of the bottle, the lower corner of which is rounded and the sides of which are tapering. B is a curved projection resembling a collar. C is the neck of the bot-

tle. This form of bottle we have denominated the "pear-shaped" bottle.

These bottles we make in different sizes, varying from one to eight ounces.

What we claim as our invention is—

The design for a mucilage-bottle, substantially as above described.

HERMON S. ADAMS.
BYRON FAY.
